DEVICE FOR TESTING, ADJUSTING AND
FOCUSING HEADLIGHTS

James Hill, Mitchell, Ontario, Canada

Application July 9, 1932, Serial No. 621,713

3 Claims. (Cl. 88—14)

This invention relates to devices for facilitating the testing, focusing and adjustment of motor vehicle headlights.

The invention has for its object to provide a device of simple and compact construction which is quickly and easily operated to test and adjust headlights in an accurate manner.

The improved apparatus is small and easily portable and does not require a large space or 10 level ground or any other special condition for its operation.

The invention consists in the construction, combination and arrangement of parts hereinafter described and more particularly pointed out in 15 the appended claims.

Referring now to the accompanying drawings, which illustrate by way of example, a convenient embodiment of the improved apparatus:

Figure 1 is a sectional elevation of the improved lamp focusing and adjusting device,

Figure 2 is a front elevation of the device,

Figure 3 is a plan of the device,

Figures 4, 5 and 6 are diagrammatic sectional elevations illustrating the operation of the device,

Figure 7 is an elevation of a support for still further facilitating the operation of the improved device,

Figure 8 is a plan view of Figure 7 partially in section,

Figure 9 is a diagrammatic side elevation illustrating the use of the device shown in Figures 7 and 8,

Figure 10 is a perspective view of an attachment for use when the supporting member shown in Figures 7 and 8 is employed.

Figure 11 is a fragmentary sectional elevation showing means for adjusting the levelling device,

Figures 12, 13 and 14 are diagrammatic plan views of the improved apparatus, and

Figure 15 is a perspective view of a modified form of supporting device.

The improved apparatus comprises a rectangular container or box 1 having opaque side, front, rear and bottom walls, which may conveniently be made of sheet metal. The top wall of the box is formed by a translucent screen or panel 2, preferably of ground glass. The front wall of the box 1 is provided with a pair of parallel, horizontal slits 3 and 4 and the panel 2 is provided with two sets of parallel index lines 5, 5^a and 6, 6^a, 6^b to cooperate with beams of light entering through the slits 3 and 4 as hereinafter described. A mirror or equivalent reflecting sur-

face 7 is mounted in the box 1, preferably at an angle of 45° with respect to the front wall and to the glass 2.

A levelling device such as a spirit level 8 is mounted at any suitable location on the box, preferably on the glass 2, and the box walls may be extended upwardly beyond the glass 2 for a suitable distance as shown in Figure 1, to protect the level 8 and also to shield the glass 2 to some extent from the exterior light.

An adjusting screw 9 is mounted in a lug 10 on the bottom of the box for a purpose to be described later.

The reflecting surface 7 and the ground glass 2 are held rigidly and accurately in position by 15 any suitable means, for example, by angular bracket members 11.

The operation of testing a headlight for correct focus will now be described with reference to the diagrams shown in Figures 4, 5 and 6.

The front wall of the box 1 is placed flat against the lens of the headlight which is indicated at 12, and the box is moved until the upper slit 3 is at the centre of the lens. The index lines 5 and 5^a are so positioned that a beam of light 13, direct from the lamp bulb 14, is reflected by the mirror 7 to illuminate the space between the lines 5 and 5^a when the slit 3 is at the centre of the lens. If the lamp is in focus a beam of light 15, reflected by the lamp reflector and passing through the lower slit 4, will be reflected by the mirror 7 at such an angle as to illuminate the space between the index lines 6 and 6^b, as indicated in Figure 4. If the lamp 14 is too far from the reflector 12 the illumination from the beam 15 will appear on the glass 2 at the right of the lines 6 as viewed in Figure 5. If the lamp is too close to the reflector the beam 15 will appear to the left of the lines 6, that is, nearer the headlight, as indicated in Figure 6.

The lamp 14 is focused by the means provided therefor on the headlight, usually by turning a screw at the back of the headlight in the appropriate direction. This adjustment is continued until the light from the beam 15 falls between the lines 6 and 6^b. Meanwhile the box is held stationary so that the light from the beam 13 remains between the lines 5 and 5^a, this condition being shown diagrammatically in Figure 12 in which the light from the beams 13 and 15 is indicated by stippling.

When the lamp has been focused the headlight is tested for correct alignment or "aim" in the following manner. The screw 9 is turned and its end bears against the lens of the headlight and

thus forces the lower part of the box 1 away from the lens, the top of the box 1 being kept pressed against the lens. The light from the reflected beams 13 and 15 will move towards the headlight, 5 the movement of the beam 15 being greater than that of the beam 13 and this adjustment of the screw 9 is continued until the light from beam 15 is just past the centre index line 6^a, see Figure 13. The headlight is now correctly aimed if 10 the levelling device 8 indicates that the box is level and assuming that the automobile is loaded at the time the adjustment is made. If the vehicle is unloaded, allowance is made for the load by continuing the adjustment of the screw 9 until the 15 light from beam 15 is just past the line 6 as indicated in Figure 14. The spacing of the lines 6, 6^a and 6^b is so calculated that the adjustment described above complies with the official regulations at the place where the adjustment is 20 made. For example, the space between the lines 6 and 6^a may be such that with the adjustment indicated in Figure 14, the top of the beam will be five inches below the centre line of the lamp at twenty-five feet from the headlight.

25 If the box is found to be not level the mounting of the headlight is now loosened and the headlight is adjusted until the levelling device 8 indicates that the box is level. The headlight is then re-clamped in position and the aiming operation 30 is complete.

The box 1 thus provides a very small and compact device by means of which focusing and aiming can be quickly and accurately effected under any conditions. The box may be made very 35 small, for example, 3½" x 4" x 1½", and it will be noticed that the size might if desired, be even further reduced by omitting that portion of the box which lies beneath the mirror 7.

When the testing is done in a garage, the operation 40 may be further simplified by means of the devices shown in Figures 7, 8 and 10. Figures 7 and 8 show a supporting member comprising a bar 16 having a longitudinal slot 17. Two clamping and self-centering devices 18 and 19 are slidably mounted on the bar 16 and are formed with angularly disposed, integral walls 20. The member 18 has a projection 21 which fits slidably in the slot 17 to prevent rotation of the member 18 on the bar 16, and a clamping screw and nut 22 are provided to secure the member in the desired position on the bar 16. The member 19 is provided with a clamping screw and nut 22^a, but may rotate as well as slide on the bar. Clamping screws 23 fitted with rubber caps 24 45 may also be mounted in bosses on the walls 20. A detachable extension device comprising two slidably connected bars 25 is adapted to project into the end of the slot 17, the whole device being arranged to be extended to a suitable length and 50 clamped in position by screws 26, the length of the bars being such that they can be extended to a total length about equal to the maximum distance between the outside edges of automobile headlights.

55 When the supporting device is to be used, the bars are assembled as indicated in Figures 7 and 8 and are held in a horizontal position in front of the headlights to be tested. The screws 22 and 22^a are loosened and the members 18 and 19 separated. The members 18 and 19 are then disposed on opposite sides of a headlight and are moved towards each other until the walls 20 engage the sides of the lamp. The parts 18 and 19, in this position, are separated by a distance 60 in excess of the length of the slots 3 and 4. When

the four points of contact of the walls 20 are in engagement with the headlight the slot 17 in the bar 16 is in position across the centre of the headlight. The nuts 22 and 22^a are then tightened and in order to prevent any slipping of the supporting device, the screws 23 are screwed in to bring the resilient heads 24 into engagement with the headlight. In placing the device in position the bars are kept horizontal so that outer extension bar 25 occupies the same position 10 relative to one headlight as the upper part of bar 16 occupies with respect to the other headlight.

When the supporting device is in position on the headlight the bars 16 and 25 are separated a short distance from the headlight lenses, and suitable means are provided to attach the testing box 1 to the bars in an upright position with respect to the lens. A suitable device for this purpose is shown in Figure 10, and consists of a 20 plate 27 having parallel lugs 28 on each side thereof, and an inverted channel or hook 29 at the top. The lugs 28 have aligned perforations arranged to register with similar perforations 31 provided in the side walls of the box 1. This 25 device is placed on the front of the box 1 as indicated in Figure 9 and a pivot pin 32 is passed through the aligned holes 30 and 31. The plate 27 is also provided with openings 33 and 34 so disposed as to register with the slits 3 and 4 30 respectively, and a projection 35 is furnished to engage the headlight lens and support the box 1 initially in upright position.

The slits in the box 1 are so arranged that the upper slit 3 registers with the slot 17 in the 35 bar 16 when the channel 29 is hooked on the bar. The operations of testing, focusing and aiming are now the same as those hereinbefore described except that the box is now centered on the lens by simply hooking the box 1 on the bar 40 16 and when the screw 9 is adjusted the box pivots on the pin 32.

When one headlight has thus been focused, aimed and levelled, the box 1 with its attachment is removed from the bar 16 and hooked on 45 the bar 25 in front of the other headlight. The same operations are repeated in the reverse order. The box 1 is already adjusted and levelled, and the first step is to loosen the headlight, if necessary, and adjust it until the beam 13 lies between 50 the lines 5 and 5^a. The lamp 14 is then moved backward or forward, if necessary, to bring the beam 15 into the position shown in Figure 13 or Figure 14 as already described.

If adjustment or replacement is necessary on 55 account of lateral displacement of the lamp, this will be indicated by the illumination on the glass 2, as the light images on the glass will taper laterally to one side or the other, instead of being rectangular.

The level 8 may be provided with an adjusting device if desired, for example, as shown in Figure 11. According to this construction, the level is provided at one end with a pivot projection 36 which engages a depression in the box 60 wall, and at the other end with a lug 37 having a screwthreaded hole engaged by a screw 38 rotatably mounted in a U-shaped bracket 39 carried by the opposite wall of the box 1. The level may be adjusted by rotation of the screw 38 and the latter is then sealed against unauthorized tampering or accidental displacement by a sleeve 40.

The foregoing description and accompanying drawings are given by way of example only and 75

modifications within the scope of the appended claims may be made without departing from the spirit of the invention. For example, weighted pointer or index arm 41 (see Figure 9) may be used if desired, instead of a spirit level, the arm being pivoted at its upper end and provided with a pointer at its lower end to cooperate with an arcuate series of graduations.

Instead of using the supporting devices shown in Figures 7 to 10, the device shown in Figure 15 may be employed. This comprises a member 42 having vertical side walls or lugs 43 and an adjusting screw 44 corresponding to the screw 9 shown in Figure 1. Aligned pins are provided at 45 whereby the box 1 can be pivotally mounted in a detachable manner between the lugs 43.

The member 42 carries a rearwardly projecting rod 46 which slidably extends through a bore in a block 47 mounted on top of a telescopic stand-
ard or post 48 arranged on a suitable base 49 adapted to stand on the ground. Clamping screws 50 and 51 are provided to secure the member 42 and post 48 in adjusted position. It is thought that the operation of this device will be clearly understood without further description as it does not affect the operation of the box 1.

What I claim is:—

1. A headlight testing device comprising a container, an index means on one wall of said container, a plurality of apertures in another wall of said container, a reflecting surface rigidly mounted in said container to reflect beams of light entering said apertures on to said index means, means for levelling said container, means to support said container in front of one or other of a pair of headlights, an attachment pivotally mounted on said container, means on said at-

5 tachment for detachably supporting said container on said supporting means in a normally upright position and means for adjusting the angular position of the container in relation to said attachment.

2. A headlight testing device comprising a container movable in any direction and having apertures in one wall, a reflecting surface rigidly mounted in said box, an index mark on another wall of said box located to receive light reflected by said reflecting surface directly from the lamp of the headlight, another index mark located to receive light reflected by said surface from the reflector of the headlight when the lamp is in focus, means for angularly adjusting said container about a horizontal axis with respect to the headlight, and further index means located to receive light reflected by said reflecting surface from the headlight reflector when the necessary angular adjustment of the box is effected by said adjusting means, and levelling device on said container to indicate "level" when the reflected light appears against said further index means and the headlight is properly aimed.

3. A headlight testing device comprising a container movable in any direction and having apertures in one wall, a reflecting surface rigidly mounted in said box, an index mark on another wall of said box located to receive light reflected by said reflecting surface directly from the lamp of the headlight, another index mark located to receive light reflected by said surface from the reflector of the headlight when the lamp is in focus, a levelling device on the box and a levelling screw on the lower part of said box and arranged to project beyond the apertured wall of said box.

JAMES HILL.
